SIPHON APPARATUS FOR HEATED ROLLS

Filed Sept. 11, 1946

UNITED STATES PATENT OFFICE

2,460,059

SIPHON APPARATUS FOR HEATED ROLLS

Hobart W. Bruker, Bordentown, N. J., assignor
to George W. Swift, Jr. Inc., Bordentown, N. J.,
a corporation of New Jersey

Application September 11, 1946, Serial No. 696,295

4 Claims. (Cl. 34—125)

1

The invention relates to steam heated rolls of the type used in paper corrugating machinery, as drier rolls, and for similar purposes, wherein it is necessary to exhaust the condensate from the interior of the roll or drum. This is usually done by a siphon pipe which is projected through the axial hole through the central hub at one end of the roll, from which point it is necessary that the siphon pipe project down and be accurately positioned close to the interior wall at the bottom of the roll. This accurate positioning is important in operation, and also it is necessary that the siphon construction be rugged and strong enough to overcome the tendency to break or shift out of accurate position, as has been prevalent among prior mechanisms used for this purpose, on account of the vibrations which occur in machinery of this character.

The present invention aims primarily to provide a siphon mechanism which will satisfy the above requirements of use, i. e., it may be accurately adjusted and held in proper operating position, and will be sufficiently strong and rugged to stay in proper operating condition without frequent attention or repairs, under the operating conditions usually encountered. In accordance with the present invention, the siphon mechanism proper extends only part way through the roll and is provided at its inner end with a bearing support, the bearing structure being held in position by retractable arms which engage the inner wall of the midsection of the roll, and which may be inserted in retracted position through the central hole in one end of the roll, into engagement with the inner end portion of the siphon mechanism proper, the arms of the bearing structure being then moved outwardly to their wall engaging position so as to hold the inner end of the siphon mechanism securely against vibration or shift in position.

Further objects and advantages of the invention will be in part obvious and in part specifically referred to in the description hereinafter contained which, taken in conjunction with the accompanying drawings, discloses a preferred form of siphon apparatus constructed to operate in accordance with the invention; the disclosure, however, should be considered as merely illustrative of the principles of the invention in its broader aspects. In the drawings:

2

Fig. 1 is a central axial section taken through a heated roll equipped with a siphon apparatus constructed to operate in accordance with the invention;

5 Fig. 2 is a section taken on the broken line 2—2 of Fig. 1, looking in the direction of the arrows.

Referring first to Fig. 1, the invention is disclosed as applied to a steam heated roll 1 having 10 supporting and bearing hubs 2 and 3 at its opposite ends, the hub 2 being provided with a central hole 4 through which the siphon mechanism may be inserted, and in the illustrated form of the invention, the bearing structure for the inner 15 end of the siphon mechanism is inserted through a similar hole 5 in hub 3.

The illustrated form of siphon mechanism is similar to that disclosed in my prior co-pending application Ser. No. 588,319 filed April 14, 1945, 20 entitled "Siphon mechanism for heated rolls" (now U. S. Patent No. 2,408,606 issued October 1, 1946) to which reference is made for a fuller disclosure of the details thereof. In brief, the illustrated form of siphon mechanism is provided with 25 an appropriate rotary steam joint 6, as known in the art, and having a steam admission pipe 7 through which steam is admitted to the interior of the roll or drum 1, and also having connected thereto an exhaust pipe 8 through which the condensate is withdrawn from within the roll.

The siphon mechanism is provided with an elongated exhaust conduit member 9 which extends through the hole 4 to the midsection of the roll, this exhaust conduit member 9 being secured 35 at its outer end to the fitting 10 which receives the pipes 7 and 8, and having therein an exhaust passageway 11 which communicates with the exhaust pipe 8.

At its inner end portion, the exhaust conduit 40 member 9 is provided with a port 12 which leads to the inner end of a hollow siphon member 13, pivoted about the pin 14 which extends between ears 15 on the exhaust conduit member 9. In 45 its operating position shown in Fig. 1, the outer end of the siphon member 13 is positioned close to the bottom of the inner cylindrical wall 16 of the roll 1 so as to withdraw the condensate. A slideable bar 17 releasably locks the siphon member 13 in this position, and when it is desired to 50 withdraw the siphon mechanism, the end cap 18

is loosened and moved somewhat to the left from the position shown in Fig. 1, to expose the outer end of bar 17. Bar 17 is then slid to the left to release the inner end of siphon member 13, and the siphon mechanism is then turned 180° until siphon member 13 falls to a position parallel and closely adjacent to the exhaust conduit member 9. The siphon mechanism may then be withdrawn from the roll. The above described form of siphon mechanism should be considered as merely illustrative, since the present invention is not concerned with many of the details thereof.

In accordance with the present invention, I provide at the inner end portion of the siphon mechanism, a bearing and supporting structure which is located in the midsection of the roll, and acts to hold the inner portion of the siphon mechanism accurately and securely in proper operating position. In the illustrated form of the invention, this bearing structure includes an elongated supporting member 19 which is positioned axially of roll 1 and is withdrawable through the hole 5 in hub 3 of the roll, the inner end portion 20 of supporting member 19 having rotary bearing engagement within a bushing 21 which is mounted in the inner end portion 22 of exhaust conduit member 9. In operation the siphon mechanism is stationary, and the supporting member 19 rotates with the roll.

To hold the supporting member 19 in position, I provide a retractable mechanism which may be adjusted between an expanded portion wherein it engages the inner cylindrical wall 16 of roll 1, and an inner retracted position wherein it lies closely adjacent to the supporting member 19 and thus frees the latter from the roll so as to enable the supporting and bearing assembly to be withdrawn endwise through hole 5. In the form shown, the supporting member 19 has fastened to it a collar 23, this collar having pivoted thereto a set of links 24. A similar collar 25 is fastened to the inner end of a sleeve 26 which is slidable along the supporting member 19, this collar 25 carrying a similar set of links 27 which are pivotally connected thereto and also to the links 24. Thus in the position shown in Fig. 1, the links 24 and 27 extend out radially to bear at their outer ends against the inner wall 16 of roll 1. This positions the bearing portion 20 of supporting member 19 accurately at the center of the roll, and in turn positions the siphon mechanism accurately in operative position, and holds the latter securely against vibration or sagging. If the sleeve 26 be shifted to the right from the position shown in Fig. 1, the links or arms 24 and 27 will assume a position parallel and closely adjacent to the supporting member 19, thus permitting the bearing structure to be withdrawn from or inserted into the interior of roll 1.

In the illustrated form of the invention the outer end of the supporting member 19 is secured by a cross-pin 28 to a central hub 29 extending inwardly from an end cap 30 which is fastened in position by bolts 31. A spacer collar 32 is interposed between the outer end of sleeve 26 and hub 29, this collar 32 being cut to the length required to hold the links 24 and 27 in the operating position shown in Fig. 1. When it is desired to withdraw the bearing and supporting structure, bolts 31 are loosened and the end cap 30 is then pulled to the right from the position shown in Fig. 1, the links 24 and 27 riding along the inner wall 16 of roll 1 during this adjustment. This movement exposes pin 28 and collar 32 so that hub 29 of end cap 30 may be disconnected from supporting

member 19. The sleeve 26 may then be slid to the right until the links 24 and 27 assume the retracted position which will enable the bearing and supporting structure to pass through hole 5.

5 While the invention has been disclosed as embodied in the above described specific form of siphon apparatus, it should be understood that changes may be made therein without departing from the invention in its broader aspects, within 10 the scope of the appended claims.

I claim:

1. Siphon apparatus for heated rolls, including an exhaust conduit member positioned centrally within the roll and extending out through one end 15 of the roll, said conduit member having a bearing portion located in the midsection of the roll, said midsection having an internal bore of enlarged size as compared to the bore of the end sections of the roll, a supporting structure located in said 20 midsection and having rotary bearing means engaging said bearing portion, said supporting structure also having outwardly extending arms engageable with the inner wall of the roll to hold the supporting structure in position, means being 25 provided to afford movement of said arms from their aforesaid wall engaging positions into positions near the axial zone of the roll.

2. Siphon apparatus for heated rolls, including an exhaust conduit member positioned centrally 30 within the roll and extending out through one end of the roll, said conduit member having a bearing portion located in the midsection of the roll, said midsection having an internal bore of enlarged size as compared to the bore of the end sections of the roll, a supporting structure located 35 in said midsection and having rotary bearing means engaging said bearing portion, said supporting structure also having outwardly extending arms engageable with the inner wall of the roll to hold the supporting structure in position, said supporting structure also including means operable from an end of the roll for moving said arms from their aforesaid wall engaging positions into positions near the axial zone of the roll.

45 3. Siphon apparatus for heated rolls, including siphon mechanism withdrawable through one end portion of the roll, said siphon mechanism having a bearing portion located in the mid-section of the roll, a supporting structure for the inner portion of said siphon mechanism, said supporting structure including an elongated supporting member located centrally within the roll and extending to the opposite end of the roll, the inner 50 end portion of said supporting member having rotary bearing engagement with the aforesaid bearing portion of said siphon mechanism, said supporting structure also having outwardly extending arms engageable with the midsection of the inner wall of the roll to hold the supporting structure in position, and means operable from said opposite end of the roll for retracting said arms to positions near the axial zone of the roll.

60 4. Siphon apparatus for heated rolls, including siphon mechanism withdrawable through one end portion of the roll, said siphon mechanism having a bearing portion located in the midsection of the roll, a supporting structure for the inner portion of said siphon mechanism, said supporting structure including an elongated supporting member located centrally within the roll and extending to the opposite end of the roll, the inner 65 end portion of said supporting member having detachable plug and socket engagement with the bearing portion of said siphon mechanism, said supporting structure also including sets of pivot-

ally mounted arms engageable with the midsection of the inner wall of the roll to hold the supporting structure in position, and means operable from the opposite end of the roll for retracting said arms to positions in the axial zone of the roll, said last mentioned means including an adjusting member movable longitudinally of the roll, said adjusting member being connected to said arms and extending to said opposite end portion of the roll.
